(57) **CLAIM**

The ornamental design for a headlight for a vehicle, as shown and described.

DESCRIPTION

This application is related to the following applications, of the inventor: Application Ser. No. 29/233,903, entitled "Surface Configuration of a Vehicle, Toy, and/or Other Replicas," now U.S. patent No. D540,216; and Application Ser. No. 29/233,904, entitled "Surface Configuration of a Vehicle, Toy, and/or Other Replicas".

FIG. 1 is a perspective view of a first embodiment of a headlight for a vehicle according to my novel design;

FIG. 2 is a front view thereof; and

FIG. 3 is a side view thereof.

FIG. 4 is a perspective view of a second embodiment of the headlight for a vehicle according to my novel design;

FIG. 5 is a front view thereof; and,

FIG. 6 is a side view thereof.

The broken lines are for illustrative purposes only and form no part of the claimed design.
